(57) **CLAIM**

The ornamental design for a massage apparatus, as shown and described.

DESCRIPTION

FIG. 1 is a perspective view of a massage apparatus showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion "9" of FIG. 1; and, FIG. 10 is an enlarged view of portion "10" of FIG. 1.

The evenly spaced broken lines in the drawings depict portions of the massage apparatus that form no part of the claimed design. The dot-dash broken lines encircling the areas of enlargement form no part of the claimed design.
